UNITED STATES PATENT OFFICE.

EDWARD J. BALLUFF, OF CHICAGO, ILLINOIS, ASSIGNOR OF ONE-HALF TO ELMER SPATZ, OF CHICAGO, ILLINOIS.

POLARITY REVERSER.

Application filed April 14, 1920. Serial No. 373,723.

To all whom it may concern:

Be it known that I, EDWARD J. BALLUFF, a citizen of the United States, residing at Chicago, in the county of Cook and State 5 of Illinois, have invented certain new and useful Improvements in a Polarity Reverser, of which the following is a specification.

My invention relates to electrical systems in which an impulse is produced by the 10 mechanical interruption of a circuit.

The general object of the invention is to reverse the direction of current through the point at which the circuit is interrupted at frequent intervals to prevent corrosion 15 and deterioration of the mechanical elements making contact at this point.

One important application of my invention is to timers for the ignition system of internal combustion engines and the object 20 thereof is more specifically to provide current reversing means built into the timer mechanism as a unitary device.

Another object is to provide means for changing the direction of current every time 25 the circuit is interrupted.

Another object is to provide a reversing arrangement in which no lead wires need carry current to moving parts.

Another object is to arrange the parts and 30 the electrical circuits so that current is never interrupted except by separation of the timer contacts so that the mechanical elements used to reverse the connections are not subject to destructive arcing.

35 Further objects and advantages of my invention will become apparent as the description proceeds.

In the accompanying drawings, Figure 1 is a plan view of a timer with the cover removed. Fig. 2 is a section on the line 2—2 40 of Fig. 1. Fig. 3 is a section on line 3—3 of Fig. 2, and Fig. 4 is a diagrammatic view of the circuits I prefer to employ.

In the embodiment of my invention selected for illustration, the timer shaft 10 extends upwardly through a sleeve 12 shown as formed integral with the lower wall 14 of a cylindrical casing 16 having a suitable cover 18. At its upper end the shaft 10 50 carries the usual cam element 20 contacting with a roller 22 to actuate a lever 24 pivoted at 26 and carrying at its outer end a contact point 28 adapted to rest against an adjustable contact screw 30. The support for the 55 lever 24 is a removable partition 32 resting on

spaced lugs 34 carried by the casing 16 and preferably attached thereto by set screws 34^a. A coil spring 36 engaging a stationary pin 38 on the partition 32 operates to hold the lever 24 against the cam 20.

The reversing mechanism I have illustrated comprises a rocker 40 housed in the casing 16 below the partition 32 and driven by an eccentric 42 carried by the timer shaft 10. The rocker has an elongated slot to 60 accommodate the eccentric 42 and is pivoted at one end at 44 to the partition 32 which is preferably of metal. The free end of the rocker carries a pair of brushes 46 and 48 which slide back and forth in contact with segments mounted on the under side of an insulating cleat 50 suitably fastened over a cut-away portion of the partition 32. The eccentric 42 has a projecting lip 52 adapted to support the weight of the rocker 75 40 and may if desired, be attached to the timer shaft 10 by a set screw (not shown) and operate to support the weight of the timer shaft itself.

Referring to Figs. 3 and 4, the contact elements I prefer to employ comprise a pair of continuous segments 54 and 56 and outer segments separated into three sections. The brushes carried by the rocker make contact at all times with the continuous segments 80 54 and 56 and each brush connects its continuous segment with the section of the adjacent discontinuous segment over which it happens to lie.

With the brushes in the position indicated 90 in dotted lines on Fig. 4, current will flow as follows—from the battery 57 through segment 56, brush 48, section 62 and wire 64, to the timer contact 30; and from the other timer contact 28 through wire 66 to section 95 72, brush 46, segment 54, wire 68, through primary winding 70 of an induction coil, and thence to a suitable ground. With the brushes in this position, this is the only circuit through which current can flow, and 100 therefore if the timer contacts open, the current will be interrupted and an electrical impulse will be generated in the secondary winding of the induction coil.

Similarly, when the brushes have moved 105 to the upper end of their stroke as shown in Fig. 4, current will flow as follows—from the battery 57 through segment 56, brush 48, section 63, wire 74, section 61, wire 76, central section 72, and wire 66, to the timer 110

contact 28; and from the other timer contact 30 through wire 64, central section 62, wire 78, section 71, wire 80, section 73, brush 46, segment 54 and thence as before through 5 the induction coil. It will be seen that when the brushes are in this position, the direction of current through the timer contact points is reversed. The end contacts 63 and 73 being directly connected by wires 74 and 80 10 to the opposite end contacts 61 and 71 the circuit through them will be identical with that last traced except for the omission of end contacts 63 and 73 and the wires 74 and 80.

15 For a four cylinder car, the parts should be arranged as illustrated; the cam 20 opening the timer contacts to deliver an impulse when the rocker 40 is in the middle of its stroke. Another impulse will be delivered 20 when the rocker is at one end of its stroke, a third as it returns to the middle position, and a fourth at the other end of the stroke. Each of these impulses will be delivered 25 with the current passing through the timer contacts in the opposite direction from that when the previous impulse was obtained. The sparking action between the contact points will therefore not tend to form a crater in one contact and a tit on the other 30 and the contact points will remain smooth and clean for a much longer period of time on this account.

The brushes 46 and 48 are preferably long enough to bridge the gaps in the discontinuous segments as they pass from one section to the next of said segments. This will 35 cut the timer contacts out of the circuit, the current flowing as follows—when the brushes are bridging the upper gap shown in Fig. 4. From the battery through segment 56, brush 48, section 62, wire 78, section 71, wire 80, section 73, brush 46, segment 54 and thence 40 through the induction coil. It would therefore be impossible to produce an impulse by 45 separating the timer contacts while the brushes were in a position to bridge either of the gaps in the outer segments. This however, does not interfere with the operation of the device as the times for opening 50 the timer contacts may be readily so placed that the impulse comes when the brushes are entirely over one set of contact elements. It will be seen that the flow of current is 55 never interrupted so as to cause a spark between the brushes 46 and 48 and the sections with which they make contact. These parts therefore may be made of material best adapted to withstand the mechanical wear of sliding contact as they will be not subjected to arcing and the resultant corrosion.

60 While I have illustrated and described in detail the preferred embodiment of my invention, it should be clearly understood 65 that the disclosure is merely for purposes of

illustration and that many modifications and variations will naturally occur to those skilled in the art. I aim in the subjoined claims to cover all such legitimate variations and modifications.

70 I claim as my invention:—

1. In a device of the character described, a casing, a partition therein, a timer shaft, timer contacts operatively associated with the shaft, a rocker pivoted to the partition, 75 an eccentric adapted to actuate the rocker, and an insulating support, said rocker and support having cooperating contacts adapted to periodically reverse the direction of current through the timer contacts.

80 2. In a device of the character described, a centrally located timer shaft, a pivoted rocker, an insulating support, cooperating contacts on the rocker, and the support, timer contacts associated with the shaft, and an eccentric on the shaft adapted to actuate the rocker.

85 3. In a device of the class described, a casing, an apertured partition in said casing, a centrally located timer shaft, timer contacts supported by said partition and operatively associated with said shaft, a rocker below said partition and pivoted thereto, an eccentric on said timer shaft adapted to 90 actuate said rocker, and an insulating support covering the aperture in said partition, said support and rocker having cooperating contacts adapted periodically reverse the direction of current through said timer contacts.

95 4. In a device of the class described, a casing, an apertured partition in said casing, a centrally located timer shaft, timer contacts supported by said partition and operatively associated with said shaft, a rocker below said partition and pivoted thereto, an eccentric on said timer shaft adapted to 100 actuate said rocker, and an insulating support covering the aperture in said partition, said support and rocker having cooperating contacts adapted to periodically reverse the direction of current through said timer contacts, said reversal being timed to occur 105 when said timer contacts are closed.

110 5. In a device of the class described, a pair of continuous segments and a pair of adjacent discontinuous segments each divided into three sections, brushes, and means for moving said brushes back and forth over said segments, timer contacts, and wiring 115 connections between said timer contacts and said segments and between certain of said segments, adapted to reverse the current through said timer contacts each time said brushes move from one section of said discontinuous segments to another section.

120 6. In a device of the class described, a pair of continuous segments and a pair of adjacent discontinuous segments each divided into three sections, brushes, and means 125

for moving said brushes back and forth over said segments, timer contacts, and wiring connections between said timer contacts and said segments and between certain of said 5 segments, adapted to reverse the current through said timer contacts each time said brushes move from one section of said discontinuous segments to another section, said brushes being adapted to move from one 10 section to another during each closed interval of said timer contacts, whereby alternate openings of said contacts are subjected to arcing in opposite directions.

7. In a device of the class described, a 15 pair of continuous segments and a pair of adjacent discontinuous segments each divided into three sections, brushes, and means for moving said brushes back and forth over said segments, timer contacts, and 20 wiring connections between said timer contacts and said segments and between certain of said segments, adapted to reverse the current through said timer contacts each time said brushes move from one section of said 25 discontinuous segments to another section, said wiring being so arranged that the circuit is never broken except at said timer contacts.

8. In a device of the class described, a pair

of continuous segments and a pair of adjacent discontinuous segments each divided into three sections, brushes, and means for moving said brushes back and forth over said segments, timer contacts and wiring connections between said timer contacts and 35 said segments and between certain of said segments, adapted to reverse the current through said timer contacts each time said brushes move from one section of said discontinuous segments to another section, said 40 brushes being long enough to bridge the gaps between adjacent sections, said bridging action operating to cut the timer contacts out of the circuit but making no other change in the current. 45

9. In an electrical system, mechanical means for periodically interrupting a current, and means for automatically changing the direction in which the current flows through said interrupting means, said direction-changing means comprising an eccentric, an insulating support and a rocker, said support and rocker having cooperating contacts, said means operating without interrupting the flow of current. 50 55

In testimony whereof, I have hereunto set my hand.

EDWARD J. BALLUFF.
